UNITED STATES PATENT OFFICE.

LOUIS W. GATES, OF NEW HAVEN, CONNECTICUT, ASSIGNOR TO C. COWLES AND COMPANY, OF NEW HAVEN, CONNECTICUT, A CORPORATION OF CONNECTICUT.

LOCKING HANDLE FOR VEHICLE DOORS.

Application filed September 20, 1921. Serial No. 502,033.

To all whom it may concern:

Be it known that I, LOUIS W. GATES, a citizen of the United States, residing at New Haven, county of New Haven, State of Connecticut, have invented an Improvement in Locking Handles for Vehicle Doors, of which the following is a specification.

In closed cars it is often very inconvenient for the driver if both the right and left hand doors are fitted only with key locks, as it is necessary in locking the doors to walk all the way around the car to lock one of them. For this reason very often the left hand door is left unlocked or is not even provided with a catch which can be locked, and the right hand door only is provided with a key controlled lock. It is, therefore, an object of this invention to provide a simple lock which may be easily and quickly locked and unlocked from the interior of the car. Such a lock is especially adapted for application to the left hand door as the driver may lock this door before leaving the car and, by locking the right hand door as he leaves the car with the usual key controlled lock, it is left secure without the necessity of going around to the other side of the same.

It is a further object of the invention to provide a lock of this type which may be locked and unlocked by merely pulling or pushing on a button conveniently located on the inside of the door.

With these and other objects in view I have devised the lock illustrated in the accompanying drawing in which,

Fig. 1 is a section of a portion of a door showing my preferred form of the lock in position.

Fig. 2 is a longitudinal, sectional view of the lock, removed from the door, taken on a plane substantially at right angles to that of Fig. 1.

Fig. 3 is a longitudinal, sectional view similar to Fig. 2 but showing a slightly modified form, and

Fig. 4 is a rear elevation of the escutcheon.

The door is represented at 10 and is provided with a recess 11 for the usual lock mechanism, not shown. The face of the door is usually covered with sheet metal or other suitable means 12, and transverse openings 13 and 14 are provided for the

passage of the lock operating spindle. This 55 spindle comprises the usual square lock operating rod 15 secured at one end in any suitable manner to the stem 16 of the handle 17, this stem being reduced to form a shoulder 18. The stem is mounted to turn in a 60 bearing in the escutcheon 19 which is secured to the outer face of the door by suitable screws 20. In the embodiment shown, the escutcheon is provided with an outwardly extending cylindrical boss 21 upon 65 which guard plate 22 is mounted to turn, this plate being substantially of the same outline as the escutcheon and, when turned to the position shown in Fig. 1, is adapted to cover the heads of the screws. The guard 70 plate is provided with a projection 23 adapted to seat in a recess in the stem 16 so that the plate turns therewith when the lock is operated.

The escutcheon 19 is provided, around the 75 bearing for the stem 16, with a series of notches 24 extending part way through the escutcheon and leading to an annular channel or groove 25, an annular rib 26 forming the outer wall of this channel. A locking 80 bar 27 is mounted to slide in a recess 28 in the stem 16 and is of sufficient length that its outer end 29 projects beyond the surface of the stem 16 and into the channel or groove 25 when it is slid to its outermost position, as shown in Fig. 1. When, however, it is moved to its innermost position, as shown in Fig. 2, the projecting end 29 is adapted to enter one of the notches 85 24 in the escutcheon and, as the bar 27 is 90 mounted to turn with the stem and spindle, the spindle will be locked against turning, but will be free to turn when this bar is in the position shown in Fig. 1, as the outer end 29 may then move around the channel 95 or groove 25. The locking bar 27 is moved back and forth in this recess from unlocking to locking position by means of a rod 30 slidably mounted in an opening 31 in the stem 16 and a groove 32 extending longitudinally of the square rod 15 in one side thereof, and having a free end provided with a button 33 on the inside of the door.

In the slight modification shown in Fig. 3, the rod 30, instead of extending in a 105 slot in one side of the square rod 15, is mounted to slide in a central, longitudinal opening 34 therein. In this form also the

stem 16 is provided with an extending elongated slot 35 in which is slidably mounted a locking bar 36 having its opposite ends projecting from the opposite sides of the stem into the annular channel or groove 25 when the spindle is unlocked. This form gives a double locking means when moved to the locking position as the locking bar extends into two opposite notches 10 in the escutcheon. This form, however, is more expensive than the form shown in Figure 1 as it is more difficult to drill the central opening 34 in the square rod 15 than to form the groove 32.

15 The spindle is secured in position in the escutcheon by means of a suitable collar 37 bearing against the inner wall of the escutcheon and secured on the stem by any suitable means such as set screw 38. If desired, a 20 suitable spring washer 39 may be provided between the guard plate 22 and the outer end of the boss 21 to prevent rattling of the spindle.

It will be apparent from the foregoing 25 that this construction provides an effective and simple means for locking or unlocking the spindle from the inside of the car, as all that is necessary is to pull out or push in the bottom 33. Also, because of the guard 30 plate 22 which is mounted to turn with the spindle and handle, when this spindle is locked this guard plate is locked over the heads of the screws preventing any possibility of tampering therewith.

35 Having thus set forth the nature of my invention, what I claim is:

1. A door lock comprising a lock operating spindle mounted to turn in the door, a stationary member secured to the outside of 40 the door, a locking bar mounted in the spindle and adapted for movement to and from engagement with the stationary member to lock and unlock the spindle, and means on the interior of the door for moving the locking bar to either position.

2. A door lock comprising a member forming an escutcheon, means for securing the escutcheon to one side of the door, a lock operating member comprising a spindle mounted in the escutcheon, a locking bar mounted on one side of said member and adapted for movement to and from engagement with the other member to lock and unlock the spindle, and a hand operated means

on the other side of the door for moving 55 the locking bar to either position.

3. A door lock comprising an escutcheon, means for securing the escutcheon to one side of the door, a lock operating spindle mounted to turn in said escutcheon, said escutcheon being provided with a recess, a locking bar movably mounted in the spindle, a rod extending longitudinally of the spindle and connected with said bar, and means on the rod at the other side of the door adapted to move the bar to and from engagement with said recess.

4. A door lock comprising an escutcheon, adapted for attachment to one side of a door, a lock operating spindle mounted to 70 turn in said escutcheon, said escutcheon being provided with a recess, a locking bar mounted to slide longitudinally of the spindle projecting at one end from the side of the spindle, and adapted for movement to and from said recess, a rod extending longitudinally of the spindle and connected with said bar and means on the other side of the door for sliding the rod to move the bar to and from the recess.

5. A door lock comprising an escutcheon, a spindle mounted to turn in the escutcheon and provided with a transversely extending recess, said escutcheon being provided with an annular groove and a recess communicating therewith, a locking bar mounted to slide in the recess in the spindle and having a projecting end adapted to extend into the groove or recess in the escutcheon, a rod extending longitudinally of the spindle and connected with said bar, and means on the rod for moving the end of the bar into either the groove or recess.

6. A door lock comprising an escutcheon adapted for attachment to a door, a lock operating spindle mounted to turn in said escutcheon, a locking element mounted in the spindle and adapted for longitudinal movement therein to and from engagement with the escutcheon to lock and unlock the spindle, a rod extending longitudinally of the spindle and connected with the locking element, and a handle on said rod at the inner side of the door for shifting the rod and locking member longitudinally of the spindle.

In testimony whereof I affix my signature.

LOUIS W. GATES.
